United States Patent Office.

JOSÉ RAMON GALLEGOS, OF HAVANA, CUBA.

Design No. 4,586, dated January 17, 1871.

DESIGN FOR A SHOW-CASE.

The Schedule referred to in these Letters Patent and making part of the same.

To all whom it may concern:

Be it known that I, JOSÉ RAMON GALLEGOS, of Havana, Cuba, have invented a new and original Design for a Show-Case; and I do hereby declare that the following is a full, clear, and exact description thereof, which will enable others skilled in the art to make and use the same, reference being had to the accompanying drawing forming part of this specification.

The figure represents my improved design.

My invention has for its object to furnish an improved design for a show-case, for displaying cigars and other articles; and

It consists in the design hereinafter more fully described.

A is the body of the case, which is made hexagonal in form, with pillars at its angles, as shown.

The body A is mounted upon a stand, B, which is made with ornamented legs or feet, as shown.

The base of the body A is circular and is formed as shown in the figure.

Upon the top of the case A is mounted a globe, C, which may have suitable words or marks printed or painted upon it.

Above or upon the top of the globe C hovers an eagle, D, bearing a scroll in its bill, upon which suitable words or symbols may be painted or otherwise formed.

The case may be made with both the globe and eagle, or with either of them, or with neither of them, as may be desired.

I claim as my invention—

1. The design for a cigar show-case, consisting of the stand B and body A, made in the form substantially as herein shown and described.

2. The design for a show-case, consisting of the stand B and body A, made in the form shown, and having a globe, C, and eagle D, either or both upon its top, substantially as herein shown and described.

JOSÉ RAMON GALLEGOS.
